UNITED STATES PATENT OFFICE.

WALTER SWIDERSKI, OF MONROE, MICHIGAN, ASSIGNOR OF ONE-HALF TO JAMES J. KELLY, OF MONROE, MICHIGAN.

GRINDING MACHINE.

Application filed July 7, 1923, Serial No. 650,066. Renewed September 9, 1925.

To all whom it may concern:

Be it known that I, WALTER SWIDERSKI, a citizen of the United States, residing at the city of Monroe, 704 West Eighth St., 5 in the county of Monroe and State of Michigan, have invented new and useful Improvements in Grinding Machines, of which the following is a specification.

My present invention has reference to an 10 attachment for grinding wheels such as are used in foundries, steel mills, etc., and whereby castings or other articles to be ground or dressed by the wheel may be fed thereto without necessitating the operator 15 standing in front of the wheel, and thereby rendering the grinding operation less dangerous to the operator, as well as permitting the operator to have a better view of his work, and also wherein the vibration usually imposed on the body of an 20 operator in such process will be entirely overcome.

A further object is to produce a feeder 25 for emery or other grinding wheels in which the work is fed to the wheel by the pressure of the operator on a suitable foot 30 pedal or lever and also wherein the support for the work may be revolved horizontally to arrange the same most conveniently with respect to the operator.

To the attainment of the foregoing and other objects which will present themselves as the nature of the invention progresses, reference is to be had to the drawings 35 which accompany and which form part of this application.

In the drawings—

Figure 1 is a side elevation of an ordinary grinding machine provided with the 40 improvement.

Figure 2 is a top plan view thereof.

Figure 3 is a sectional view on the line 3—3 of Figure 1.

Figure 4 is a sectional view on the line 45 4—4 of Figure 2.

Figure 5 is a sectional view on the line 5—5 of Figure 4.

Fig. 6 is an enlarged detail view of the removable jaw of the feed block.

The frame of the grinding machine is indicated in the drawings by the numeral 1. As both the frame and the mechanism for turning the emery wheel 2 are old and well-known in the art, a detailed descrip-

tion thereof will not be attempted. The 55 frame 1 is provided, in the usual manner, at one side thereof and adjacent to the wheel 2, with an outstanding bracket 3 slotted to receive therethrough a binding bolt 4 that also passes through a slotted 60 somewhat thickened plate 5.

In addition to the slot through which the bolt passes the plate 5 is provided adjacent to its outer end with a round opening, and in the present instance I pass 65 through this opening a tubular post 6. The post is secured at one end of a substantially U-shaped working supporting member 7. At its outer and open end the frame has journaled between the arms thereof a 70 grooved wheel 8.

Arranged for slidable movement between the arms of the work supporting member 75 there is the channeled base of a feed block 9. The feed block has at its inner end an upstanding lug 10. A preferably ribbed jaw member 18 has a socket 19 to receive the lug 10 therethrough.

On its outer end there is secured to the block 9 a cable 11 which is trained over 80 the grooved wheel 8 and which has attached to its free end a weight 12.

Secured to the under face of the feed block 9, below its lug 10 there is a cable 85 13 which is trained over a sheave wheel 14 whose shaft is journaled in suitable bearings between the arms of the work holder or support 7. The cable 13 is trained through the tubular post 6 which is either integrally formed with or secured 90 on the work holder 7 and has its outer end secured, as at 15 to a pedal 16 which is pivoted, as at 17, to a leg of the frame 1.

The casting or other article to be ground 95 is placed upon the work holder or support 7, the same being in the path of contact with the jaw 18 on the lug 10 on the feed block 9. The operator places his foot on the pedal 16, and by depressing the same 100 will cause the feed block to move the work longitudinally over the work holder or support 7 toward the emery wheel 2. The pressure of the work against the wheel is, of course, regulated by the weight of pressure 105 on the pedal 16, and when the pedal is relieved of such weight the weight 12 will move the feed block 9 and the removable jaw 18 to its initial outward position.

on the feed holder 7. Such movement of the feed block 9 is limited by it contacting engagement with the grooved wheel 8.

With my improvement, the operator may 5 station himself at any convenient point with respect to the wheel, and as the work holder is mounted for both longitudinal and rotary movement, the casting or work thereon may be accurately fed to the wheel. 10 The operator is in a position to at all times observe the grinding action without danger to himself.

I have herein set forth a simple and satisfactory embodiment of my invention, but 15 I wish to state that I do not desire being restricted to the precise structural details herein set forth as the invention is to be restricted only to the scope of the claims hereunto appended.

20 Having described the invention, I claim:—

1. In combination with a frame having a revoluble grinding wheel thereon, of means for advancing work to the wheel, comprising a plate pivotally associated with the frame and susceptible to rotary and longitudinal adjustment thereon, a work holder pivotally associated with the plate, a feed block carrying a jaw slidable on the work holder, weighted means holding the block in one position, and pedal operated means for moving the block in the direction of the grinding wheel.

2. In combination with a frame having a revoluble grinding wheel thereon, and an outstanding slotted bracket on one side of the frame, of a means for feeding work to the grinding wheel, comprising a slotted plate pivotally associated with the slotted bracket and susceptible to revoluble and longitudinal movement thereover, a bifurcated work holder pivotally associated with the plate, a work feed block having a chan-

neled base received in the bifurcated portion of the work holder, a jaw on the feed block, weighted means for moving the feed block 45 outwardly on the work holder and pedal operated means for moving the feed block in an opposite direction to feed the work toward the grinding wheel.

3. In combination with a frame having 50 a revoluble grinding wheel thereon and a slotted bracket extending from one side of the frame, of a means for supporting and feeding work to the grinding wheel, comprising a somewhat thickened slotted plate 55 arranged over the bifurcated bracket and adjustably pivoted thereto to permit of a rotary and longitudinal movement of the plate on the bracket, said plate having its outer end formed with an opening, a work 60 supporting member which is bifurcated for the major portion of its length and which has at one end a depending hollow tubular post which is received through the opening in the plate, said work supporting member 65 having sheave wheels journaled in the bifurcated portion thereof, a work feed block having a base whose sides are channeled and are received in the bifurcated portion of the support, said work feed block having an up- 70 standing lug, a removable jaw on the lug, a cable secured to the rear of the block journaled over the outer pulley of the support and having a weight secured thereto, a second cable connected to the forward end 75 of the block, journaled over the sheave wheel at the forward end of the support and guided through the tubular post, and a pedal pivotally secured to the frame and to 80 which the last mentioned cable is attached.

In testimony whereof I affix my signature.

WALTER SWIDERSKI.
